Primary Examiner—Jeffrey Asch(74) *Attorney, Agent, or Firm*—Cary & Kelly, LLP; Charles C. Cary(57) **CLAIM**

The ornamental design for an apparatus for a wireless network connection, as shown and described.

DESCRIPTION

FIG. 1 is a perspective view as seen from the upper left and front of an apparatus for a wireless network connection showing our new design;

FIG. 2 is a perspective view as seen from the lower right and rear thereof;

FIG. 3 is a front elevational view thereof;

FIG. 4 is a right side elevational view thereof;

FIG. 5 is a rear side elevational view thereof;

FIG. 6 is a left side elevational view thereof;

FIG. 7 is a top plan view thereof; and,

FIG. 8 is a bottom plan view thereof.
